UNITED STATES PATENT OFFICE.

HENRY W. GRIFFIN, OF NEW YORK, N. Y., ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,254,038.

Specification of Letters Patent. Patented Jan. 22, 1918.

Continuation of application Serial No. 712,531, filed July 31, 1912. This application filed April 28, 1913. Serial No. 763,999.

To all whom it may concern:

Be it known that I, HENRY W. GRIFFIN, a citizen of the United States, residing at New York, in the county of New York and State 5 of New York; have invented certain new and useful Improvements in Railway Signaling, of which the following is a specification.

My invention relates to railway signaling 10 for single track over which traffic moves in both directions, such for example, as for stretches of single track between passing sidings.

I will describe one form of railway signaling embodying my invention, and then point out the novel features thereof in 15 claims.

The present application is a continuation 20 of my application filed July 31, 1912, Serial No. 712,531, for railway signaling.

In the accompanying drawings, Figure 1 is a diagrammatic view showing a stretch 25 of railway track having applied thereto one form of railway signaling system embodying my invention. Figs. 2 and 3 are views similar to Fig. 1 but showing the effect on the apparatus of the presence of a car or train at two points in the stretch. Figs. 4 and 5 are views showing modifications of 30 certain relays shown in the preceding views.

Similar reference characters refer to similar parts in each of the several views.

Referring to the drawings, A is a stretch 35 of track between two passing sidings C and D. Traffic through the stretch A from west to east is governed by signals 1, 3 and 5, and traffic through the stretch A from east to west is governed by signals 2, 4 and 6. The stretch A is divided into a plurality of 40 track sections a^1 , a^2 and a^3 , each of which track sections is provided with a track circuit comprising a source of current b and a track relay T^1 , T^2 or T^3 . As here shown, a pair of opposing signals is located adjacent 45 each junction of two adjacent track sections, although I do not wish to limit myself to this particular arrangement of signals. Adjacent one end of the stretch A is a preliminary track section a^1 which is also provided with a source of current b and a track relay T^4 .

Each signal is provided with a controlling circuit, each of which circuits is controlled 50 by a signal relay provided for the corre-

sponding signal. As here shown signal relay R^1 controls signal 1, relay R^2 controls signal 2, relay R^3 controls signal 3, and so on. For example, the circuit for signal 2 is from battery B^9 through wire 9, armature contact 10 of signal relay R^2 , wire 11, signal 2, wire 12 and common wire 0 to battery B^9 . The circuits for the other signals are similar to that for signal 2; hence, they need not be traced in detail herein.

Each signal relay is provided with a controlling circuit each of which circuits is controlled by the track relay for the track section over which the corresponding signal governs traffic and each of which circuits is also controlled under certain conditions by the signal relay for the signal next in advance governing traffic in the same direction. For example, the circuit for signal relay R^2 is from battery B^5 through wire 13, armature contact 14 of signal relay R^4 , 75 wires 15 and 16, armature contact 17 of track relay T^3 , wire 18, signal relay R^2 , wire 19, common wire 0 to battery B^5 . The circuits for the other signal relays are similar to that just traced, except that as here shown the 80 circuit for signal relay R^5 is controlled only by armature contact 31 of track relay T^3 , because this is the relay for the last signal of the stretch and there is no preliminary section at that end.

It will be seen from the foregoing that when any signal relay is deenergized, it will open the circuit of the signal relay for the signal next in the rear governing traffic in the same direction, thereby placing the last- 90 mentioned signal at danger; and that the opening of the signal relay for the last-mentioned signal will, in turn, open the circuit of the signal relay for the next signal in the rear governing traffic in same direction, thereby placing that signal at danger, and so on.

The circuit for each signal relay is provided with a branch around the armature contact of the signal relay which controls 100 that circuit, and this branch circuit is, in turn, controlled by an auxiliary relay X^1 , X^2 or X^3 , etc. For example, the branch for the circuit of signal relay R^2 comprises wire 20, armature contact 21 of relay X^4 and wire 105 22. It will be seen that when relay X^4 is energized, the opening of relay R^2 will have no effect on the circuit for relay R^2 . The

- branch for each signal relay circuit is similar to that for the circuit of signal relay R^2 , hence they need not be traced in detail herein. Each auxiliary relay is provided 5 with a "pick-up" circuit and also with a "holding" circuit, which latter circuit includes a front contact of that auxiliary relay, and is, therefore, also a "stick" circuit. For example, the "pick-up" circuit for relay 10 X^4 is from battery B^6 through wire 23, armature front contact 24 of relay R^4 , wire 25, armature contact 26 of relay R^5 , wire 27, relay X^4 , wire 33, back contact 34 of relay X^5 , and wire 28 to common wire 0 and battery B^6 . It will be seen that this circuit can be closed only when relay R^4 is energized and relay R^5 is deenergized and when auxiliary relay X^5 is deenergized. The "holding" circuit for relay X^4 is from 15 battery B^6 through wire 23, armature back contact 24 of relay R^4 , wire 29, armature contact 32 of relay X^4 , wire 30, relay X^4 , wire 33, back contact 34 of relay X^5 , wire 28 to common wire 0 and battery B^6 . It will be seen that this "holding" circuit is 20 closed only after relay X^4 has been picked up and when relay R^4 is deenergized. 25 With the arrangement of pick-up and holding circuits for relay X^4 shown in Fig. 30 1 and just traced, there is a brief interval of time between the opening of the front point of contact 24 and the closing of the back point of this contact, during which 35 interval relay X^4 is on open circuit. I have found by experience that when relay R^4 is a 40 usual commercial relay having the usual contact adjustment, this interval is so short that relay X^4 remains closed; hence, it is not absolutely necessary to make relay X^4 slow- 45 acting or to adjust contact 24 in a special manner. Relay R^4 may, however, if desirable, be constructed as indicated in Fig. 4; that is, the contact 24^a may be so constructed and adjusted that when the relay 50 opens, the back point of this contact closes before the front point of the same contact opens. Or, if desired, contact 24 of relay R^4 may remain as indicated in Fig. 1, and relay X^4 may be made slow-acting as indicated in Fig. 5. 55 The "pick-up" and "holding" circuits for each of the other auxiliary relays X^1 , X^2 , etc., are similar to the circuits just traced for relay X^4 . Referring now particularly to Fig. 1, it will be seen that when the entire stretch A is unoccupied by a car or train, each signal relay R^1 , R^2 , etc., is energized and the circuit for each signal governing traffic through 60 the stretch is, therefore, closed so that each of these signals is in clear position. Referring now particularly to Fig. 2, when a westbound car or train W enters the stretch A from siding D, it deenergizes track relay T^3 , thereby opening the circuit for signal 65 relay R^2 so that signal 2 behind the car or train W changes to danger indication. The opening of track relay T^3 also opens the circuit of signal relay R^5 thereby causing signal 5 to change to danger indication. The 70 opening of signal relay R^5 opens the circuit of signal relay R^4 thereby causing signal 3 to change to danger indication, and the opening of signal relay R^3 opens the circuit of signal relay R^1 thereby causing signal 1 75 to change to danger indication. It will be seen, therefore, that the presence of the car or train W in track section a^3 causes each of the signals 1, 3 and 5, governing traffic in the direction opposite to the direction of 80 movement of the car or train, to indicate danger, thereby prohibiting the passage of a car or train through the stretch A in the direction opposite to the direction of movement of car or train W. It is desirable, however, that following movements in the same direction should be permitted, but that following cars or trains should be separated by the distance between two successive signals. That is, it is desirable that as a car or train 85 proceeds through the stretch A, each signal behind the car or train governing traffic in the direction of movement of the car or train, should change to clear indication as soon as the car or train leaves the territory 90 which is protected by such signal. This feature of control is obtained by means of the auxiliary relays X^1 , X^2 , etc., and by the branch circuits controlled by these relays in the manner which I will now explain. 95 Referring still to Fig. 2, it will be seen that the opening of signal relay R^5 closes the pick-up circuit for auxiliary relay X^4 so that this relay is now closed. Similarly, it will be seen that the opening of relay R^3 100 caused relay X^2 to be closed and that the opening of relay R^1 causes relay X^1 to be closed. 105 Referring now to Fig. 3, as the car or train W passes from track section a^3 to track section a^2 , it opens track relay T^2 thereby deenergizing signal relay R^4 . Inasmuch as relay X^4 is already closed, the opening of relay R^4 closes the "holding" circuit 110 of relay X^4 and this latter relay, therefore, remains closed. When the car or train passes entirely out of track section a^3 , track relay T^3 closes, thereby closing the circuit of signal relay R^2 through armature contact 21 of auxiliary relay X^4 so that signal 2 changes 115 to clear indication, thereby permitting a following westbound car or train to enter stretch A. Similarly, as the car or train W passes from track section a^2 to track section a^1 , it allows the circuit of signal relay R^4 120 to close through the contact of auxiliary relay X^2 , thereby permitting signal 4 to change to clear indication. Similarly, as the car or train passes from track section a^1 into track section a^4 , it allows relay R^6 to close, thereby 125 130

- permitting signal 6 to change to clear indication. As the car or train passes from section a^2 into section a^1 , the closure of track relay T^2 allows signal relay R^4 to be closed 5 as just explained. The closing of relay R^4 opens the holding circuit for relay X^4 so that the latter relay then opens, but since relay R^4 is then closed the circuit for signal relay R^2 is completed at contact 14 of the latter relay as shown in Fig. 1. Similarly, 10 when the car or train passes from section a^1 to section a^4 the closure of relay T^1 closes relay R^6 , thereby opening relay X^2 and thus transferring the circuit for relay R^4 from a contact of relay X^2 to a contact of relay R^6 .
- With the arrangement of apparatus and circuits here shown, when the car or train W passes from track section a^3 into track section a^2 , the closing of track relay T^3 20 closes the circuit for signal relay R^5 so that signal 5 changes to clear indication. Although relay R^5 is then closed and relay R^4 open, relay X^4 does not close because its circuit includes back contact 34 of relay X^4 which relay is closed. Similarly, as the car 25 or train passes from track section a^2 to track section a^1 , the closing of track relay T^2 closes the circuit of signal relay R^5 (relay R^5 being already closed) and signal 3, therefore, changes to clear indication. Also as the car 30 or train passes from track section a^1 into track section a^4 , the closing of track relay T^1 closes the circuit of signal relay R^1 so that signal 1 changes to clear indication.
- When an eastbound train enters preliminary section a^4 , it opens track relay T^4 thereby causing signals 6, 4 and 2 to change to danger indication. The operation of the system during the passage of this eastbound 35 car or train through the stretch A is similar to the operation hereinbefore explained for the passage of a westbound car or train, hence it need not be explained herein.
- It will be noted that by means of the preliminary section a^4 , the possibility of two cars or trains moving in opposite directions entering the stretch A past signals 1 and 2 at the same instant is avoided.
- Although I have herein shown and described only one form of railway signaling system embodying my invention, it is understood that various changes and modifications may be made therein within the scope of the appended claims without departing from the spirit and scope of my invention.
- Having thus described my invention, what I claim is:
1. In railway signaling, a stretch of single track, signals located at intervals for governing traffic in one direction through the stretch and other signals located at intervals for governing traffic in the other direction through the stretch, a signal relay for the control of each signal, a circuit for each signal relay each of which circuits in- 60 cludes a contact of the signal relay for the next signal in advance governing traffic in the same direction, track relays connected with the stretch for controlling the circuits of the signal relays, an auxiliary relay for each signal relay and having a front contact connected in shunt to the said front contact of the signal relay, a pick-up circuit for each auxiliary relay including a front contact of the corresponding signal relay and a back 70 contact of the signal relay for an adjacent signal governing traffic in the opposite direction, and a holding circuit for each auxiliary relay including a back contact of the corresponding signal relay. 80
  2. In combination, a stretch of single track divided into a plurality of controlling sections, a pair of opposing signals located substantially at each junction of adjacent sections for governing traffic in opposite directions, a signal relay for the control of each signal, a circuit for each signal relay each of which circuits is controlled by a front contact of the signal relay for the signal next in advance governing traffic in the same direction, a track relay connected with the rails of each controlling section for the control of the circuit of the signal relay for each signal governing traffic through the section; a branch for each signal relay circuit around 90 the signal relay contact which controls such circuit, an auxiliary relay for the control of each branch, a closing or pick-up circuit for each auxiliary relay including a front contact of the signal relay whose first-mentioned contact is bridged by the corresponding branch circuit and a back contact of the signal relay for the adjacent opposing signal, and a holding or stick circuit for each auxiliary relay including a front contact of the auxiliary relay and a back contact of the signal relay whose first-mentioned contact is bridged by the corresponding branch. 100
  3. In combination, a stretch of single track, signals located at intervals for governing traffic in one direction through the stretch and other signals located at intervals for governing traffic in the other direction through the stretch, a signal relay for the control of each signal, a circuit for each signal relay each of which circuits is controlled by a front contact of the signal relay for the next signal in advance governing traffic in the same direction, track relays connected with the stretch for controlling 110 the signal relay circuits, an auxiliary relay for each signal relay and having a front contact connected in shunt to the said front contact of the signal relay; a pick-up circuit for each auxiliary relay including a front contact of the corresponding signal relay and a back contact of the signal relay for an adjacent signal governing traffic in the opposite direction and a back contact of the auxiliary relay for the last-mentioned signal. 120
  4. In combination, a stretch of single track, signals located at intervals for governing traffic in one direction through the stretch and other signals located at intervals for governing traffic in the other direction through the stretch, a signal relay for the control of each signal, a circuit for each signal relay each of which circuits in- 130

relay; and a holding circuit for each auxiliary relay, including a back contact of the corresponding signal relay and a front contact of the auxiliary relay.

5. In combination, a stretch of railway track, signals governing traffic in one direction through said stretch and other signals governing traffic in the other direction through the stretch, a line circuit for each signal for the control thereof, track circuits for the stretch for controlling said line circuits, means for controlling the line circuit for each signal by the line circuit for the signal next in advance governing traffic in the same direction, an auxiliary relay for each signal for removing the line circuit for the signal from control by the line circuit for the signal next in advance, and means controlled by a train entering the stretch for actuating the auxiliary relay for each signal governing traffic in the direction in which the train is moving.

6. In combination, a stretch of railway track, signals governing traffic in one direction through said stretch and other signals governing traffic in the other direction through said stretch, a signal relay for each signal, track circuits for the stretch for controlling said signal relays, means for controlling each signal relay by the relay for the signal next in advance governing traffic

35
5. In combination, a stretch of railway track, signals located at intervals for governing traffic through said stretch in one direction, a line circuit for each signal for the control thereof, track circuits for the stretch for controlling said line circuits, 40 means for controlling the line circuit for each signal by the line circuit for the signal next in advance, an auxiliary relay for each signal for removing the line circuit for the signal from control by the line circuit for the signal next in advance, and means controlled by a train entering the stretch and 45 moving in the direction in which said signals govern traffic for actuating each of said auxiliary relays.

50
55 In testimony whereof I affix my signature in presence of two witnesses.

HENRY W. GRIFFIN.
